UNITED STATES PATENT OFFICE.

ARTHUR R. EAST, OF DELIA, TEXAS, ASSIGNOR OF ONE-HALF TO J. J. BECKHAM, OF LIMESTONE COUNTY, TEXAS.

COTTON-CHOPPER-TOOL-LIFTING MECHANISM.

1,252,674.

Specification of Letters Patent.

Patented Jan. 8, 1918.

Original application filed April 24, 1917, Serial No. 164,137. Divided and this application filed September 10, 1917. Serial No. 190,469.

To all whom it may concern:

Be it known that I, ARTHUR R. EAST, a citizen of the United States, residing at Delia, in the county of Limestone and State 5 of Texas, have invented certain new and useful Improvements in Cotton-Chopper-Tool-Lifting Mechanism, of which the following is a specification.

This invention relates to lift mechanism 10 for cotton chopper tools and is a division of my original application filed April 24th, 1917, Serial Number 164,137.

The particular feature embodied in the invention is a hand and footlifting mechanism 15 capable of independent operation whereby either the hand or the foot operations may be performed, and the tools or hoes either lifted without disturbing their fixed adjustment or their elevation adjusted 20 as desired.

In carrying out the invention a pair of lifting members are connected with the hoe shaft, one of these members supporting the shaft and the other being idle. The supporting member has flexible connection with 25 a hand adjusting lever which controls the fixed elevation of the hoe shaft; while the idle member has connection with a foot lever which is free to swing. The flexible connection permits the foot lever to be depressed and the hoe shaft lifted without altering the elevation of the same.

The invention will be more readily understood from a perusal of the following specification and by reference to the accompanying drawings, in which an example of the invention is illustrated and wherein:

Figure 1 is a view of a machine embodying the invention, portions of the machine 40 being omitted and other portions being illustrated in section and in elevation,

Fig. 2 is a detail of one of the hoes, and Fig. 3 is a plan view of the machine.

In the drawings the numeral 1 designates 45 a U-shaped frame having bearing boxes 2 in which an axle 3 is rotatably confined, said axle being mounted in ground wheels 4 in the usual manner. At the central portion of the axle a friction gear disk 5 is keyed to 50 slide laterally into contact with a friction pinion 6 keyed to slide on a hoe shaft 7. A tension spring 8 is coiled about the axle between the hub of the disk and a tension col-

lar 9 rotatably mounted on the axle and having inclined teeth or lugs meshing with similar teeth of a bearing sleeve 10. The sleeve 10 is fastened to one end of a yoke 11 which has another sleeve 12 at its other end, both of said sleeves being loosely confined on the axle, but held against lateral displacement. 60 An arm 13 projects from the collar 9 by which it may be rocked for displacing said collar and compressing the spring 8.

An arch-bracket 14 is fixed on the yoke and inclines upwardly therefrom as is best 65 shown in Fig. 1. A locking segment 15 is mounted on this bracket and has pivoted thereon a bell-crank adjusting lever 16 which has connection from its short leg with the arm 13 by means of a link 17. By means 70 of this hand lever the collar may be rocked. Another locking segment 18 is mounted on this bracket and has a hand lever 19 pivoted thereon intermediate its ends. The low depending end of said lever has connection 75 with a shifting rod 20 mounted over the hoe shaft 7 in ears 21 on the yoke. This rod carries a shifting-fork 22 straddling the pinion 6. By adjusting the hand lever 19 the pinion may be adjusted laterally of the disk 80 5 and the gear ratio varied.

The hoe shaft 7 extends through a shaft-sleeve 23 illustrated in Figs. 1 and 3. One end of the sleeve 23 is confined in a collar 24 on the yoke 11 and the other end abuts the 85 hub of a hoe spider 25. Intermediate the ends of the sleeve a collar 26 is clamped thereon. This collar is suspended by a link 27 depending from the end of an arm mounted on a transverse shaft 29 arranged to rock 90 in bearing boxes 30 mounted on the frame 1. By rocking this shaft the sleeve 23 carrying the hoe shaft and the yoke are either swung up or down. On the spider 25 hoe-shanks 31 are fastened. In Fig. 2 is shown the angle 95 at which each hoe is mounted. This causes the hoe to enter and leave the ground gradually, the point of the hoe entering first. The hoe blade 33 is suitably fastened on the shank.

The chopping mechanism which is supported by the link 27 from the arm 28 may be adjusted vertically at will. For rocking the shaft 29 an arm 42 is adjustably fastened on the shaft. A chain or other flexible connection 43 extends from the upper end of

the arm to a hand lever 44 pivoted on a locking segment 45 mounted on the side of the frame 1. By swinging this lever the chopping mechanism is either raised or lowered 5 and may be minutely set so that the hoes will chop at a regular depth. Another arm 46 extends upwardly from the shaft 29 at the other side of the frame. A pitman 47 is pivoted to the upper end of the arm 46 and 10 extends rearward to a bell-crank foot lever 48 pivoted on a bracket 49 projecting from a transverse foot-bar 50. Should it be desired to lift the chopping mechanism where the stand was thin or to carry it over an obstruction the driver merely places his foot 15 on the lever 48 and presses the latter downward, whereby the shaft 29 is rocked and the chopping mechanism lifted. The chain 43 permits this action without disturbing the 20 adjustment of the cutting depth of the hoes.

At the forward end of the frame 1 a tongue 52 is pivoted on an arch support 53 and has its rear end swingable across an adjacent arch support 51. The rear end of 25 the tongue has pivoted connection with a link 54 pivoted to a bell-crank lever 58 mounted on a bracket 59 carried by the frame. A pitman 60 extends from the lever 58 to a hand lever 61 pivoted on a segment 30 62 at the rear portion of the frame. It will be seen that by swinging the lever 61 the rear end of the tongue will be swung and the machine guided.

The foregoing description and illustration 35 clearly express the invention, but it is to be understood that said illustration is merely

an exemplification and the invention may be carried out in various other ways.

What I claim is:

1. In a cotton chopper, the combination 40 with a main frame, a driving axle supporting the frame, and ground wheels supporting the axle, of a tool carrying shaft suspended from the frame and radially from the axle longitudinally of the frame, a supporting 45 member carrying the shaft, a rock shaft mounted transversely of the frame and connected with the supporting member for raising and lowering the same, a foot lever mounted on the frame and having operative 50 connection with the rock shaft for rocking the same, and a hand lever mounted on the frame and having flexible connection with the rock shaft for rocking the same, said flexible connection permitting the operation of 55 the foot lever without disturbing the adjustment effected by the hand lever.

2. In a cotton chopper, the combination 60 with a frame and a cultivating mechanism mounted to swing thereon, of mechanism for adjusting the cultivating mechanism to a fixed elevation to operate at a regular depth and for lifting said mechanism without disturbing said adjustment including a rock shaft mounted on the frame 65 and supporting the chopping mechanism, a foot lever mounted on the frame and having positive connection with the rock shaft, and a hand lever mounted on the frame and having flexible connection with the rock shaft. 70

In testimony whereof I affix my signature.
ARTHUR R. EAST.
